UNITED STATES PATENT OFFICE.

RALPH J. SHIPLEY, OF WATERBURY, CONNECTICUT, ASSIGNOR TO GEORGE W. MCGILL, OF NEW YORK, N. Y.

PROCESS OF MAKING PAPER-FASTENERS.

SPECIFICATION forming part of Letters Patent No. 416,510, dated December 3, 1889.

Original application filed September 5, 1887, Serial No. 248,874. Divided and this application filed September 8, 1888. Serial No. 284,910. (No model.)

To all whom it may concern:

Be it known that I, RALPH J. SHIPLEY, a citizen of the United States, residing at Waterbury, in the county of New Haven and State of Connecticut, have invented new and useful Improvements in the Process of Making Paper-Fasteners, of which the following is a specification.

My invention has for its object an improved method of making the duplex-pronged metallic fasteners known as "McGill's Fasteners," and the consequent production of such fasteners free from burr-surfaces with unvarying exactness in the irregularity of the length of the shanks of each fastener and the close and set parallel contact of all the folded parts of the fastener, and the doing of this in a simple, practical, rapid, economical, uniform, and automatic manner.

The improved method is hereinafter set forth in the claims, reference being made to the accompanying drawings, which exhibit a machine suitable for holding, receiving, and bending the metallic blanks into the desired form.

In the drawings, Figure 1 represents an elevation of the machine. Fig. 2 is a plan view of the same. Fig. 3 is a vertical longitudinal sectional view taken on the line $\alpha\alpha$, Figs. 1 and 2. Fig. 4 is an elevation of the receiver or sheath for holding the blanks. Figs. 5 and 6 are detail views, in larger size, of the pin and secondary head. Figs. 7, 8, 9, 10, and 11 are detail views showing the various stages of bending the blank.

In the drawings, the letter A indicates the main base-frame of the machine, and A' its upright portion.

The shaft B for driving the mechanism is journaled in bearings upon the upright frame A', and said shaft carries the fly-wheel E, driving-clutch D, cams C C', and crank-wheel Q. The clutch D is connected and disconnected by the clutch-lever D'. A belt driven by suitable power is used upon the pulley of the clutch D to operate the machine. The connecting-rod R extends from the crank-wheel Q to a sliding head P in guide-slides O O in the frame A' to move the head up and down. Upon the face of the sliding head P is an anvil P', and this anvil is shown as rest-

ing upon a bracket which is part of the sliding head, and said anvil is held to the head P by a set-screw 4, and is adjustable vertically by the set-screw P². Upon the upper end of the sliding head P is a bracket-arm S, and passing vertically through said bracket-arm is a screw T, that is attached at its lower end to the secondary head U, which is free to slide in guides in the frame A, and the jam-nuts on such screw connect it by and to the bracket S and cause the head U to be moved in unison with the sliding head P. Upon the back of the secondary head U is a socket V, one side of which is slotted. (See Figs. 5 and 6.) Within the socket V is a pin-holder W, and the pin X passes through this holder W and through the heads U and P, and the frame A is slotted at α' for this pin X. The screw Y passes through the holder W and clamps the pin X in place; but said pin may be removed or fed forward as worn.

There is a pin 5 secured to the holder W, and said pin passes through the slot in socket V and through the fork or slot of the lever Z, and there is a nut 6 and washer 7 connecting the holder W and lever Z, the said pin 5 being free to move up and down in the forked or slotted end of the lever Z as the head P and secondary head U are raised and lowered. This lever Z Z' is pivoted at A² to a lug of the frame A', and the end of this lever has a roller or friction-wheel Z'', which is acted on by the cam C, which imparts to said lever and the pin X a forward motion, the retractile spring B' imparting the return movement.

There is a bracketed table F secured to the frame A' at its upper part, and upon the said table is the slotted dovetailed block G, into which is received the dovetailed end block h'' of the blank-holding sheath H, which is filled with superimposed metal blanks with the burr-surface of each and every blank facing in the same direction. The sheath H is affixed in the slotted dovetailed block G by its dovetailed end block h'', and in such position delivers by gravity to the block G all the fastener-blanks contained therein with their burr-surfaces facing down.

The interior shape of the sheath or case H

corresponds with the shape of the fastener-blanks, as does the interior of the slotted block G, to which the case H is affixed. The case H is filled with metal blanks for making 5 paper-fasteners, superimposed therein with the burr-surfaces of each and every blank facing in the same direction. This may be done by hand, but is preferably and automatically accomplished by affixing the case 10 beneath the punching-dies of a machine for punching paper - fastener blanks such as shown and described in my patent, No. 382,911, of May 15, 1888, filed jointly with the application of which this is a division.

15 The sheath or case H is slotted to its hollow center on one side from its dovetailed end block h'' clear through its other end, and is provided with a spring block or support g', movable lengthwise in said slot, upon which 20 the blanks lie as they are fed down into the sheath, and this support is pressed down by the blanks as they accumulate. When the sheath is filled, it is reversed and affixed by means of its dovetailed end block h'' in the 25 slotted block G of the machine proper. The spring block or support g' is released and helps by its weight to increase the gravity of the descent of the fastener-blanks through the case into the slotted block G and down 30 on the table F. If increased gravity is required, it is obtained by securing a weight to the ring in the head of the set-screw g'' in the spring-block g'.

An arm h', Fig. 1, is employed to clamp and 35 hold the sheath H in the block G. The forward end of the table F is made with guideways f f', in which works the slide-block I, and to the block I is connected the feed-blade J. This blade J is moved back and forth above the 40 table F and below the block G and between the end guides f' f', and said blade pushes or takes the bottom blank from the pile of blanks in the slotted block G and delivers it to the bending mechanisms with the surface of the 45 blank facing the same as it did in the slotted block—to wit, downward. These end guides f' f' are set so that the distance from the center or diameter of the pin X to one of them is greater than that to the other, to enable the 50 feed-blade J to deliver the fastener-blank under the pin X in such position that the blank may be folded out of center, or so that one of its arms or shanks will be longer than the other, for an object hereinafter described.

55 The slide-block I has an arm I', connecting it to the rod K and carriage K', and there is a lever L, whose slotted upper end is connected by a pin to the carriage K', and said lever L is pivoted at A³ to a lug upon the frame A', 60 and the end of the lever L carries a friction-roller M, which is acted upon by a cam C' upon the driving-shaft B to impart to the carriage K', rod K, arm I, and pushing-blade J a forward movement, a spring N retracting the 65 lever L to deliver the blanks.

There are sliding stocks D' D' in the frame A', and connected to them are the jaws E' E',

which, with the stocks, can be moved horizontally. The spring-arms F' F' are connected at their lower ends by bolts 8 to the 70 sides of the upright frame A', and the upper ends of said springs bear against the outer ends of the stocks D' D' and act to press them and the jaws E' toward each other, and tend to keep the jaws closed, but allow them 75 to be pressed apart.

Upon a pivot at 10 is the bent lever g' g'', and connected to it and to the frame A' is the helical spring H'. The upper end of this bent lever is slotted, and connected to it by the 80 pivot-pin h is the clearer G'. This clearer G' passes through one bracket of the table F, and its bent end projects over the anvil P'. This clearer and bent lever are operated by the slide-head P, the foot-piece of g' passing 85 under the lower side of said slide-head P, so that the descent of the slide-head moves the clearer G' forward, while its ascent allows the spring H' to force the lever backward and move the clearer out of the way.

The operation of the machine in forming a paper-fastener from the blank is as follows: The metal blanks a² from the sheath H and slotted block G are pushed or removed one at a time and delivered by the feed-blade J 95 between the end guides f' f' upon the upper edge of the jaws E' E' and beneath the pin X with their burr-surfaces facing downward, as in the slotted block G. The descent of the slide-head P brings down the projecting pin X, as seen in Fig. 7, and said pin, pressing the blank at a point a little to one side of its center, bends it into a V shape, as shown in Fig. 8, with one of its members or sides of the V longer than the other, and the 100 burred surface of the blank consequently facing outward. The further movement of the pin X as it acts on the rounding corner of the jaws opens them and bends the blank as seen in Fig. 9, and the pin and bent blank descend between the jaws, and as the pin X passes below the jaws they close upon the blank, bending it around the pin, and, bringing its arms together, hold it in place, as seen in Figs. 1 and 10. The further movement of 110 the mechanism now withdraws the pin X, leaving the blank held by the jaws E', and the slide-head P is raised and the anvil connected thereto is brought to bear upon the open round head of the blank and flattens the 115 same into the form shown in Fig. 11, and at the same time the pin X has been raised with the heads and is projected by the lever Z Z', and by this time another metal blank has been pushed upon the upper edges of the 120 jaws E' by the feed-blade J, and the parts are again in the position shown in Fig. 7, ready by the descent of the pin X to form another 125 fastener, which operation opens the jaws E' and releases the first-made fastener, so that it is free to fall into a receptacle provided for the purpose. In case the fasteners so formed should not fall away when released, but should stick upon the anvil P', the clearer G',

moving across the face of the anvil, acts to remove the fastener and cause it to fall into the receptacle provided for that purpose.

To produce the McGill duplex-pronged fastener invariably free from all burr-surfaces, with one of the fastener-shanks invariably and regularly longer than the other to facilitate their after separation, and the finished fastener with all its folded parts invariably in close-set parallel contact, was almost impracticable under the method of manufacture heretofore practiced, and could only be accomplished, and then indifferently uniform, by a great expenditure of time, labor, and skill.

It will be observed that according to my improved method the fastener-blanks are superposed in the holding sheath or case H with their burred surfaces all facing in the same direction, and that the case H thus filled is affixed in the slotted block G in a manner to deliver the blanks to it in similar position, and that consequently each fastener-blank is successively pushed from the base of the superimposed column of blanks below the base of the block G and automatically fed to the bending mechanism in similar position—that is, with its burr-surface facing downward—so that the forcing of the blank down between the clamping-jaws E' E' by the descension of the pin X, as seen in Fig. 9, helps to rub the burr from the duplex shanks, while the rising of the heading-anvil P', and its consequent swaging or pressing the open round head of the blank into form against the under side of the jaws E' E', as shown in Fig. 11, accomplishes the same end for the part of the blank forming the fastener-head; that all the burr that remains is on the outside surface of the fastener thus formed, and consequently may afterward be readily and cheaply removed by the tumbling process. Further, that according to my improved method of manufacture the fastener-blank being carried by the guideways f' f' out of center under the pin X, the pin X consequently folds the blank out of center and forms the round open head therein, as shown in Fig. 10, with one arm of the folded blank longer than the other, and that the rising of the anvil P' then flattens, swages, and sets this head in manner to securely hold the arms in such position—that is, differing in length—to facilitate their after separation when put in use. Further, that, according to my improved method the fastener-blank being first formed with its shanks of the correct varying lengths and in close parallel contact, with the center of the blank forming a round open head, and the shanks being securely held in this position by the clamping-jaws E' E', while the round open head is closed and swaged flat by being pressed between the face of the anvil P' and the under surface of the jaws E' E', this pressure on the outside surface of the head from below and above tends to swage, draw, or spread the metal on the outside surface of the head, and thereby set

the fastener with all its folded parts in close parallel contact, and to form and set each and every fastener uniformly and invariably alike, without any tendency of the folds to spring apart when the fastener is released from the forming-machine.

I claim as my invention—

1. The method herein described of manufacturing metallic fasteners, which consists in superimposing in a column a series of cut or stamped metallic blanks with their burr-surfaces all facing in the same direction, successively moving the blanks from the column with their burr-surfaces in the same direction, and bending the blanks into duplex-pronged fasteners, with the burr-surfaces outermost, substantially as set forth. 75

2. The method herein described of manufacturing metallic fasteners, consisting in a series of cut or stamped metallic blanks superimposed in a column with their burr-surfaces all facing in the same direction, being successively moved from the column with their burr-surfaces in the same direction, and bending the blanks into duplex-pronged fasteners, with the burr-surfaces outermost, substantially as set forth. 80

3. The method herein described of manufacturing metallic fasteners, which consists in superimposing in a column a series of cut or stamped metallic blanks with their burr-surfaces all facing in the same direction, successively moving the blanks from the column with their burr-surfaces in the same direction, and bending the blanks into fasteners having duplex prongs differing in length, with the burr-surfaces outermost, substantially as set forth. 95

4. The method herein described of manufacturing metallic fasteners, consisting in a series of cut or stamped metallic blanks superimposed in a column with their burr-surfaces all facing in the same direction, being successively moved from the column with their burr-surfaces in the same direction, and bending the blanks into fasteners having duplex prongs differing in length, with the burr-surfaces outermost, substantially as set forth. 100

5. The method herein described of manufacturing metallic fasteners, which consists in superimposing in a column a series of cut or stamped metallic blanks with their burr-surfaces all facing in the same direction, successively moving the blanks from the column with their burr-surfaces in the same direction, bending the blanks into two prongs and a circular open head with the burr-surfaces outermost, and then flattening and closing the circular open head, substantially as set forth. 115

6. The method herein described of manufacturing metallic fasteners, consisting in a series of cut or stamped metallic blanks superimposed in a column with their burr-surfaces all facing in the same direction, being successively moved from the column with their burr-surfaces in the same direction, bending

the blanks into two prongs and a circular open head with the burr-surfaces outermost, and then flattening and closing the circular open head, substantially as set forth.

5 7. The method herein described of manufacturing metallic fasteners, which consists in superimposing in a column a series of cut or stamped metallic blanks with their burr-surfaces all facing in the same direction, successively moving the blanks from the column with their burr-surfaces in the same direction, bending the blanks into two prongs differing in length and a circular open head with the burr-surfaces outermost, and then flattening and closing the circular open head, substantially as set forth.

8. The method herein described of manufacturing metallic fasteners, consisting in a series of cut or stamped metallic blanks superimposed in a column with their burr-surfaces all facing in the same direction, being successively moved from the column with their burr-surfaces in the same direction, bending the blanks into two prongs differing in length and a circular open head with the burr-surfaces outermost, and then flattening and closing the circular open head, substantially as set forth.

9. The method herein described of making metallic fasteners, which consists in folding a metal blank into two prongs and forming them with an open circular connecting-head, pressing the two prongs together, and flattening and closing the head, substantially as set forth.

35 10. The method herein described of making metallic fasteners, which consists in folding a metal blank into two prongs differing in length and forming them with an open circu-

lar connecting-head, pressing the two prongs together, and flattening and closing the head, substantially as set forth.

11. The method herein described of manufacturing metallic fasteners, which consists in superimposing a series of blanks in a column, successively moving the blanks from the column and bending them into two prongs and a circular open head, and then flattening and closing the head, substantially as set forth.

12. The method herein described of manufacturing metallic fasteners, consisting in a series of blanks superimposed in a column, being successively moved from the column and bent into two prongs and a circular open head, and then flattening and closing the head, substantially as set forth.

13. The method herein described of manufacturing metallic fasteners, which consists in superimposing a series of blanks in a column, successively moving the blanks from the column and bending them into two prongs differing in length and a circular open head, and then bending and closing the head, substantially as set forth.

14. The method herein described of manufacturing metallic fasteners, which consists in a series of blanks superimposed in a column, being successively moved from the column and bent into two prongs differing in length and a circular open head, and then bending and closing the head, substantially as set forth.

In testimony whereof I affix my signature in presence of two witnesses.
